UNITED STATES PATENT OFFICE.

ADDISON B. TINSLEY, OF ANSTEAD, WEST VIRGINIA.

INSULATOR.

999,683.

Specification of Letters Patent. Patented Aug. 1, 1911.

Application filed March 1, 1910. Serial No. 546,642.

To all whom it may concern:

Be it known that I, ADDISON B. TINSLEY, a citizen of the United States, residing at Anstead, in the county of Fayette and State 5 of West Virginia, have invented a new and useful Insulator, of which the following is a specification.

It is the object of this invention to provide an insulator, one of the component 10 parts of which will be so disposed with respect to the other, that the first named part will be well adapted to deflect the water falling upon the insulator, beyond the contour of the other part, so that it will be difficult 15 for the water to find its way within the insulator.

Another object of the invention is to provide an insulator, the parts of which are adapted to serve as clamps, between which 20 the wire is carried, novel means being provided for forcing the clamps together.

Another object of the invention is to provide an insulator, so constructed that the wire which passes through the insulator will 25 be held apart from the lower edge thereof, thus preventing any leakage of electricity over the outer, wet face of the insulator.

With the above and other objects in view, the invention consists in the novel construction 30 and arrangement of parts hereinafter described, delineated in the drawings and claimed, it being understood that, within the scope of what is claimed, divers changes may be made, without departing from the 35 spirit of the invention.

In the drawings,—Figure 1 is a transverse section of one form of my invention; Fig. 2 is a transverse section, the cutting plane being at right angles to the cutting plane of 40 Fig. 1; Fig. 3 is a transverse section of a modified form of the invention; Fig. 4 is a transverse section of the form of the invention delineated in Fig. 3, the cutting plane of Fig. 4 being at right angles to the cutting 45 plane of Fig. 3; and Fig. 5 is a top plan of a modified form of lug which may be employed in either of the forms delineated in the preceding figures.

In the drawings, the numeral 1 denotes 50 the support upon which the insulator is mounted; and this support may be represented by the cross arm of a telegraph pole, or the like. Fixed in, and rising from the support 1, are spaced standards 2. Between 55 these standards 2 is located the base 3 of the insulator, the base 3 being notched at

its outer edges, to fit between the standards 2. Resting upon the base 3 is the cap 4, the same being adapted, like the base 3, to fit between the standards 2. Rising from the 60 base 3 is a lug 5, preferably formed integrally with the base, and this lug 5 is adapted to register in an opening 6 in the lower face of the cap 4. In the upper face of the lug 5 grooves are made, for the reception 65 of the wires. It is of course obvious that there may be any number of these grooves; in the present instance, I have shown three of them, although a greater or less number might be employed. These 70 grooves 7 in the upper face of the lug 5 are adapted to coöperate with similar grooves, designated by a like numeral, and located in the lower face of the cap 4. In these co-operating grooves 7 of the lug 5 and the cap 75 4, the wires 8 are located.

The upper, outer face of the cap 4 is rounded as denoted by the numeral 11, in order that water falling upon the insulator may be properly deflected. The cap 4, at 80 its lower periphery, is made somewhat larger than the base 3, and by this construction, the water falling upon the rounded surface 11 of the cap 4 will be deflected beyond the periphery of the base 3, thus keeping 85 the interior of the insulator dry at all times. The cap 4 is provided upon its lower face with a peripheral flange 9, and a rib 10 extends transversely of the lower face of the cap beneath the periphery of the flange 9. This rib 10 depends below the lower 90 edge of the flange 9, and by this construction, the wire 8, is, as clearly seen in Fig. 2 of the drawings, maintained apart from the flange 9. The rib 10, being located within 95 the periphery of the flange 9, will be kept dry, and, since the wire 8 is spaced apart from the lower edge of the flange 9, there will be no opportunity for leakage of electricity from the wire 8 upon the wet round- 100 ed face 11 of the insulator.

At their free extremities, the standards 2 are provided with heads 12. A bridge-piece 14 enters into the structure; and this bridge-piece at one end, is provided with diverging 105 prongs 15. At the other end of the bridge-piece 14, and in one side thereof, there is a notch 16. The prongs 15 may be made to straddle one of the standards 2, to be engaged beneath the head 12 of the said 110 standard. Then, by swinging the bridge-piece laterally, the notch 16 may be made to

engage the other standard, beneath the head thereof. Mounted in the bridge-piece 14, intermediate the ends thereof, is a set screw 17, and, by advancing this set screw in the 5 bridge-piece, the cap 4 may be crowded down upon the base 3, thus clamping the wires 8 between the cap 4 and the base 3.

If desired, the modified form illustrated in Figs. 3 and 4 may be employed. In such 10 case, the standards 18 are rectangularly bent, to receive hooks 19 at the ends of a bail 20, the bail 20 in such case, replacing the bridging member 14 of Figs. 1 and 2. Into this bail 20, the set screw 27 is introduced, and the set screw serves, as before, 15 to clamp the base and the cap together. In this case, the lug 21 which rises from the base is modified from the showing of the preceding figures. The upper face of 20 this lug consists of a series of steps 22, the lower face of the cap being shaped to conform to these steps. The rib 23 is likewise modified, the same being stepped, as denoted by the numeral 24, to conform to the 25 steps 22 of the lug 21. The advantages incident to this construction are, that the wires 8, may be carried out of the insulator at different heights, and thus, the wires may be crossed, as they pass out of the insulator, and extended in different directions, 30 without coming into contact with each other, and short-circuiting.

In Fig. 5 a further modification of the invention is shown, the invention consisting 35 in altering slightly the wire-receiving groove in the upper face of the lug of the base portion of the device. It is to be understood that this lug delineated in Fig. 5, may be applied to either of the forms of the invention hereinbefore described. This modified lug 25 has upon its upper face, a channel 26 for the reception of a wire, the channel, in its intermediate portion, being enlarged as denoted by the numeral 27. By 40 this construction, the wire may be wrapped where it passes through the insulator, the wrapping being disposed in the enlarged portion 27 of the groove; or, if necessary, the enlarged portion 27 of the groove may 45 be employed to retain a splice in the wire, or any other enlargement therein.

From the foregoing it will be seen that by manipulating the set screw 17 in either form of the invention, the cap 4 will be

bound firmly upon the base 3, thus securing 55 the wires in place. Moreover, any water falling upon the rounded upper surface 11 of the cap 4 will not only be deflected outwardly, but, deflected outwardly beyond the contour of the base upon which the cap is 60 mounted, thus preventing the water from finding its way into the insulator. The insulator is so constructed that a plurality of wires may be crossed as they leave the insulator, and extended in different directions, 65 without short-circuiting the wires. And finally, a wrapping of any sort may surround the wire, within the contour of the insulator, without interfering with the operation of the device. 70

The bridge-piece 14 of Figs. 1 and 2 may readily be swung laterally and tilted upwardly for removal from the standards 2, and the hooks 19 upon the ends of the bail 20 will permit the said bail to be swung 75 downwardly at its upper end, so that the cap may readily be removed.

Having thus described the invention, what is claimed is:—

1. In a device of the class described, 80 spaced standards provided with heads; a cap located between the standards; and a freely removable, cap engaging bridge piece slideable in the direction of its length to engage beneath the head of one standard and 85 fitable in a plane at right angles to the standards to engage beneath the head of the other standard.

2. In a device of the class described, 90 spaced standards adapted to be mounted in a fixed support and provided with heads; a cap disposed between the standards; a bridge piece provided at one end with spaced prongs to engage beneath one head when the bridge piece is slid longitudinally, the 95 bridge having a notch in its side face to engage beneath the other head when the bridge piece is tilted in a plane at right angles to the standards; and a clamping device in the bridge piece to bear upon the cap. 100

In testimony that I claim the foregoing as my own, I have hereto affixed my signature in the presence of two witnesses.

ADDISON B. TINSLEY.
